UNITED STATES PATENT OFFICE.

CONRAD A. JOHNSON, OF JAMESTOWN, NEW YORK.

WINDOW-SCREEN.

1,235,694.

Specification of Letters Patent. Patented Aug. 7, 1917.

Application filed May 1, 1916. Serial No. 94,579.

To all whom it may concern:

Be it known that I, CONRAD A. JOHNSON, a citizen of the United States, residing at the city of Jamestown, in the county of Chautauqua and State of New York, have invented certain new and useful Improvements in Window-Screens, of which the following, taken in connection with the accompanying drawings, is a specification.

The invention relates to hollow sheet metal window and screen frames, and the object of the improvement is to provide a simple and strong sheet metal frame for both window and screen construction in which a rib is raised from the sheet metal lengthwise of the frame side and a tubular slotted piece is slipped onto the same to extend over and hold the screen fabric and filling strip and also serve for a holding strip for guard wire or window glass, thereby providing means for the easy rewiring of frames of this type without the use of screws, putty, nails or similar devices; and the invention consists in the novel features and combinations hereinafter set forth and claimed.

In the drawings, Figure 1 is an elevation of the screen frame showing the covering and holding strips in position. Fig. 2 is an elevation with a sectional view alongside thereof showing the corner of the screen frame with a portion broken away to show the spring for the guide strip. Fig. 3 is a perspective view of a portion of the top or bottom side of the screen frame showing the construction of the same and the arrangement of the raised rib along the side of said screen frame and the tubular covering strip for said raised rib. Fig. 4 is a perspective view of the angular corner brace. Fig. 5 is a perspective view of a portion of the tubular slotted flat sheet metal cover and holding strip. Fig. 6 is a modification of the holding strip shown in Fig. 5; and Fig. 7 shows further adaptation of said modification shown in Fig. 6 with the modified form of the screen side adapted to receive a guard wire or window glass and hold it firmly against the frame side and the grooved edge and guide strip. Fig. 8 is a perspective view of one of the springs for engaging the guide strip. Fig. 9 is a sec-

tional view of the cross bar at line X—X in Fig. 1.

Like characters of reference refer to corresponding parts in the several views.

The numeral 10 designates the tubular sheet metal frame sides which are preferably made of one strip of metal folded centrally lengthwise at the inner point 11 and the contiguous folded inner portion formed in a lengthwise groove 13 opening sidewise along the inner edge to receive the filling strip 14, which is preferably of wood for the screen fabric 15. The remaining portions of the strip of metal are formed in a lengthwise tube and the two edges are united on the outer side in the top and bottom sides in a flat return bend or double seam 12, as shown in Fig. 3.

The lateral frame sides 20 are usually provided with lengthwise grooves 28 in their outer edges to slidably receive the guide strips 29 therein, one at each side. The groove 28 is formed by shaping a return bend in one edge of the sheet metal strip which bend is spaced so as to interlock with a lengthwise return bend in the other edge, and the three thicknesses of sheet metal so placed together at 30 are then united by spot welding or similar means so as to attach the sheet metal edges firmly together. The leaf springs 31 are attached in the groove 28 to bear against the guide strip 29 in holding engagement, and are shaped in the outwardly curved form with the turned end 32. A pin 33 is inserted through the end 32 and through the side walls of the groove 28 thereby holding the spring 31 with freedom of movement at its unattached end. The central outwardly curved portion of the spring 31 bears against the guide strip 29. The guide strip 29 may be made in any suitable manner so that it is stiff and strong.

To cover the strip 14 and groove 13 a T-shaped rail or rib 17 is bent from the sheet metal tube side into the flat T-shaped form lengthwise along the inner edge of the groove 13 and a flat tubular sheet metal strip 18 is provided with a lengthwise slot 19 which fits over the rib 17 and onto the neck or stem 16. The inner edge of the flat tubular strip 18 is extended over the groove

13 and onto the edge of the screen fabric 15 thereby covering the groove 13 and the manner of attaching the screen fabric to the screen side, protecting the same from the 5 elements and retaining the filling strip and screen fabric in position.

In the modification of the frame side shown in Figs. 6 and 7, the tubular frame side 20 is formed from one strip with the 10 groove 13 along its inner edge and with the T-shaped rib 17 along the groove 13 and the inner edge of the tubular frame side 20. The tubular retaining strip 21 is provided with the attaching lengthwise slot 19 to receive 15 the rib 17 therein the same as strip 18. The change in the formation of the strip being the angular bend 22 along the inner portion 23 to provide for the reception of the edge of a guard wire or a pane of glass 24 in 20 said angular bend 22 and between the strip 21 and the frame side 20 either with or without the screen fabric 15.

The corners of the frame 10 are preferably mitered as shown at 25 and the angular 25 sheet metal corner brace 26 is inserted in the adjacent ends of the tubular frame sides 10 and 20 fitting closely within the same so that said frame sides may be soldered to the angular brace 26 thereby attaching said 30 frame sides strongly to one another. The filling strips 14 are preferably not mitered, it being easier to fit said filling strips to place if square ended, as also the cover strips 18, as shown in Fig. 1. The frame is provided with lifts 27 for sliding the frame up 35 and down, one of the lifts 27 being preferably placed on the side opposite the springs 31 to aid in placing the frame on the guides 29.

40 When it is necessary to insert a cross piece 34 in a screen frame, it is of course essential that it should have the wire attaching groove 13 on each edge, as shown in Fig. 9. The cross piece 34 is preferably 45 made of two strips of sheet metal with the groove 13 bent in each edge of one of said strips and the other strip bent channel shaped over the turned up edges of the first strip and spot welded at 35, thereby holding 50 the two strips firmly together. Two parallel spaced ribs 17 are bent up in the sheet metal so as to slidably receive the tubular strip 18 thereon and substantially abut one another so as to give a pleasing appearance 55 for the grooved side of the strip 34 and protecting the edge of the screen fabric 15 each side of said cross piece 34.

It is apparent that the cover strip 18 provides a guard for the edge of the wire 60 fabric 15, and the cover strip 21 for the edge of the guard wire or glass 24 as well as a cover and holding means. It also beautifies the frame side covering the method of attachment, yet being removable from said 65 frame side so that either the screen fabric

or the glass can be quickly and easily removed by sliding the tubular strip 18 or 21 endwise from the rib 17. While covering the method of attachment it at the same time forms a part of that method of attachment holding firmly against the filling strip 14 and the cloth 15, thereby retaining said filling strip and cloth or screen fabric firmly in the groove 13 without the use of screws, putty, nails or similar devices, thereby overcoming all difficulties in rewiring the screen frame or replacing the guard wire or a pane of glass.

I claim as new:

1. In a metal screen, a frame, each of the 80 sides of said frame comprising a strip of metal folded lengthwise of its central portion, said folded central portion shaped in a lengthwise groove opening sidewise, the remaining portion of said strip formed in 85 a tube with the edges of said strip squeezed together along the outer edge of the frame side so as to provide a line of reinforcement throughout said last named frame side, screen wire, and a filling means to hold said 90 screen wire in said groove.

2. In a screen, a frame having grooves to receive the screen fabric, filling strips for holding the fabric in the grooves, finishing strips extending over the filling strips and 95 concealing the latter, and inter-engaging means between the frame and finishing strips for holding the latter in place and for permitting removal of said finishing strips from the frame by a relative movement between the two.

3. A screen comprising a metallic frame having a groove along the inner edge, screen wire and a filling strip to hold said screen wire in said groove, a rib on said frame 105 alongside said groove enlarging outwardly from the side of said frame, and a metallic strip having a slot therein enlarging inwardly to slidably fit said rib and cover said groove to hold said filling strip in position and retain said screen wire.

4. A screen comprising a metallic frame having a groove along the inner edge, screen wire and a filling strip to hold said screen wire in said groove, a rib on said frame 115 alongside said groove enlarging outwardly from the side of said frame, a metallic strip having a slot therein enlarging inwardly to slidably fit said rib and cover said groove to hold said filling strip in said groove, said 120 metallic strip having an angular opening therein over said groove to hold the edge of a guard or pane of glass.

5. In a metal screen, a frame comprising 125 sheet metal tubular sides having sidewise grooves therein along their inner edges, screen wire and means for holding said screen wire in said sidewise grooves, a rib alongside said sidewise grooves, and a tubular slotted strip fitting over said rib and cov- 130

- ering said sidewise groove to retain said filling strip and wire cloth in position.
6. In a metal screen, a frame comprising sheet metal tubular sides having sidewise grooves therein along their inner edges, screen wire and means for holding said screen wire in said sidewise grooves, a T-shaped rib bent from the sheet metal alongside said sidewise groove, and a flat slotted 10 tubular metal strip to slidably fit over said rib and cover said sidewise groove to retain said filling strip and wire cloth in position.
7. In a screen, a frame, a cross-piece having a pair of longitudinal grooves, wire in 15 the grooves, filling strips for holding the wire in the grooves, ribs adjacent the pair of grooves, and strips slidably fitted over the ribs to cover said grooves and filling strips.
8. In a screen, a metal frame the sides of 20 which are centrally folded lengthwise to provide grooves opening outwardly on the front face of the frame, said sides being further folded to form side edge grooves one of 25 the walls of the latter being formed of an intermediate folded part and the other wall being formed of interengaging edge parts of said sides to provide a wall of three thick-
- nesses, screen fabric in said first grooves, and filling strips to hold the fabric in position. 30
9. In a screen, a frame having grooves to receive the screen fabric, filling strips for holding the fabric in the grooves, finishing strips extending over the strips and concealing the latter, and inter-engaging means between the frame and finishing strips for holding the latter in place and for permitting removal of said finishing strips from the frame by a relative movement between the two, said finishing strips having parts overhanging said first named grooves to enable a guard or the like to be engaged with and held in place by said overhanging parts. 35
10. In a screen, a frame having grooves to receive the screen fabric, filling strips to hold the fabric in said grooves, and finishing strips slidably connected to the frame and extending over said filling strips to hold the latter in place. 40

In testimony whereof I have affixed my signature in the presence of two witnesses.

CONRAD A. JOHNSON.
